UNITED STATES PATENT OFFICE.

GEORGE ADOLPHSON AND JAMES F. CASHMAN, OF MILFORD, MASSACHUSETTS, ASSIGNORS TO DRAPER COMPANY, OF PORTLAND, MAINE, AND HOPEDALE, MASSACHUSETTS.

DESIGN FOR A STOP-MOTION DETECTOR.

SPECIFICATION forming part of Design No. 34,104, dated February 19, 1901.

Application filed January 25, 1901. Serial No. 44,767. Term of patent 14 years.

To all whom it may concern:

Be it known that we, GEORGE ADOLPHSON and JAMES F. CASHMAN, citizens of the United States, residing at Milford, in the county of Worcester and State of Massachusetts, have invented and produced a new and useful Design for a Stop-Motion Detector, of which the following is a description, reference being had to the accompanying drawings, forming a part thereof.

Figure 1, in side elevation, shows a stop-motion detector illustrating our design; and Fig. 2 is a right-hand edge elevation thereof.

The leading feature of our design for a stop-motion detector consists of an elongated loop-like body portion provided with substantially parallel opposite extensions, one of which is shaped to present at or near its extremity a pigtail or eye.

In the drawings the stop-motion detector is shown as comprising an elongated loop-like

body portion a , which is provided with substantially parallel straight and opposite extensions a' a'' , one of the same, as a'' , being shaped to present a pigtail or eye a^3 at or near its extremity, the opposite extensions at their adjacent portions forming one side of the body portion, as a^x .

Having fully described our design, what we claim, and desire to secure by Letters Patent, is—

The design for a stop-motion detector, substantially as herein shown and described.

In testimony whereof we have signed our names to this specification in the presence of two subscribing witnesses.

GEORGE ADOLPHSON.
JAMES F. CASHMAN.
